**CABINET FOR ELECTRICAL APPARATUS
OR SIMILAR ARTICLE**

John A. Sandor, Stamford, Conn., assignor to Sorensen
and Company, a corporation of Connecticut

Application April 24, 1956, Serial No. 41,190

Term of patent 14 years

(Cl. D26—5)

FIG. 1

FIG. 2

Fig. 1 is a perspective view of a cabinet for electrical apparatus or similar article embodying my new design; and

Fig. 2 is an end elevational view thereof.

The dominant features of my design reside in the portions shown in full lines.

The other end of the cabinet shown in Fig. 2 is identical in appearance to the side shown.

I claim:

The ornamental design for a cabinet for electrical apparatus or similar article, as shown and described.
